(57) **CLAIM**

The ornamental design for a fluid routing plug, as shown and described.

DESCRIPTION

FIG. 1 is a rear right-side perspective view of a fluid routing plug of our new design;

FIG. 2 is a front right-side perspective view thereof;

FIG. 3 is a rear left-side perspective view thereof;

FIG. 4 is a front left-side perspective view thereof;

FIG. 5 is a top plan view thereof;

FIG. 6 is a bottom plan view thereof;

FIG. 7 is a rear elevational view thereof;

FIG. 8 is a front elevational view thereof;

FIG. 9 is a right-side elevational view thereof; and,

FIG. 10 is a left-side elevational view thereof.

The broken lines shown in the figures are for the purpose of illustrating portions of the fluid routing plug and form no part of the claimed design.
